UNITED STATES PATENT OFFICE.

JACOB H. BLEY, OF NEW YORK, N. Y.

CLASP.

SPECIFICATION forming part of Letters Patent No. 406,021, dated July 2, 1889.

Application filed October 22, 1888. Serial No. 288,862. (No model.)

To all whom it may concern:

Be it known that I, JACOB H. BLEY, of New York, in the county and State of New York, have invented a new and Improved Clasp, of which the following is a full, clear, and exact description.

The invention relates to clasps of that kind commonly used on suspenders, supporters, neckties, &c.

10 The object of the invention is to provide a new and improved clasp which is very simple and durable in construction, and can be easily opened and closed and securely locked in position.

15 The invention consists of two arms loosely connected with each other, and of a slide fitting over the said two arms and serving to open and close the latter and to lock the same in place.

20 The invention also consists of certain parts and details and combinations of the same, as will be fully described hereinafter, and then pointed out in the claims.

Reference is to be had to the accompanying 25 drawings, forming a part of this specification, in which similar letters of reference indicate corresponding parts in all the figures.

Figure 1 is a front elevation of the improvement. Fig. 2 is a side elevation of the same, 30 in a closed position, with the slide in section. Fig. 3 is a sectional side elevation of the same in an open position. Fig. 4 is a sectional plan view of the same on the line $x-x$ of Fig. 1. Fig. 5 is a side elevation of a modified form 35 of the improvement, and Fig. 6 is a like view of another modification with the slide in section.

The improved clasp A consists of three principal parts—namely, the arms B and C 40 and a slide D fitted over the said two arms B and C.

The arm B is preferably straight, and is provided at one end with inwardly-bent teeth E, and at the other end of the said arm are 45 formed flanges F, bent over the tape G supporting the clasp.

The arm C is provided at one end with inwardly-extending teeth H, fitting into the teeth E of the arm B. The opposite end of 50 the said arm C is formed into an outwardly-extending incline I, adapted to close over the

upper end of the arm B. On the arm C are formed the inwardly-extending flanges J, fastened to the extreme lower end of the tape G next to the flanges F. In the middle of the 55 incline I, near its outer end, is formed a stop K, and a similar stop K' is formed on the end of the arm C, near the teeth H. A like stop K² is formed near the teeth E on the arm B.

The slide D is formed in the shape of an 60 elongated ring, as is plainly shown in Fig. 4, and is provided at each end with a slight extension D', of which the operator takes hold to move the slide upward or downward on the arms B and C.

Instead of connecting the arms B and C with each other at the end of the tape G, as illustrated in Figs. 1, 2, and 3, I may also hinge the arms B and C, as illustrated in Fig. 5. The hinge N is located at the inner end of the incline I and below the flanges F of the arm B. The arms B and C may also be connected with each other by a spring O, (illustrated in Fig. 6,) said spring being secured by one end to the inside of the arm B, near the flange F, and 70 by its other end to the inside of the arm C, near the teeth H.

The operation is as follows:

When the slide D is in its lowermost position, as shown in Figs. 1 and 2, the arms B 80 and C are closed, and may engage with their teeth E and H the article to be grasped. The arms B and C are now in a closed position, and the slide D prevents their opening by fitting closely over the said arms. The slide D 85 is prevented from sliding off of the arms by the stops K' and K². Now, when the operator desires to open the clasp, he moves the slide D upward, so that it passes over the incline I, which is thus moved toward the flanges F 90 of the arm B, and consequently the lower part of the arm C swings outward, thereby releasing the article grasped between the teeth E and H. The upward movement of the slide D is limited by the stop K. It will be seen 95 that as the two arms are loosely connected with each other the conjunction of the incline I with the arm C forms the pivot-point when the slide D is moved upward or downward. When the slide D is moved downward, the 100 outwardly-extending arm C is moved inward toward the arm B by the said slide D, and the

incline I again assumes its outermost position, as before described, and shown in Figs. 1 and 2. As the slide D fits snugly over the arms B and C, it remains in any position to which 5 it is moved on the said arms by the operator, thereby locking the arms in either an open or a closed position.

Having thus fully described my invention, I claim as new and desire to secure by Letters 10 Patent—

1. In a clasp, the combination, with a tape, of two arms secured on the said tape, of which one is provided with an incline, and a slide

fitted over the said arms to open and close the same, substantially as shown and described. 15

2. In a clasp, the combination, with a tape, of two arms secured on the said tape, of which one is provided with an incline, a slide fitted over the said arms to open and close the same, and stops formed on the said arms to limit 20 the sliding motion of the said slide, substantially as shown and described.

JACOB H. BLEY.
